GRAVITY-FED MIRROR-SILVERING HAND GUNS

Joseph Muller, Queens, N. Y.

Application December 21, 1953, Serial No. 399,461

9 Claims. (Cl. 299—86)

This invention relates to gravity-fed mirror-silvering 15 hand guns.

It is conventional to silver mirrors with plural solutions which have been mixed manually before application to the back of a mirror for precipitation of silver thereon. Customarily one of the solutions includes silver nitrate and another a reducing agent. These solutions if mixed in certain concentrations and permitted to stand too long explode violently. The higher its temperature the more readily the mixture explodes. Moreover, due to rapid deterioration the mixture should be used within a few seconds after mixing. Hence, mirror silverers must work at great speed and under dangerous conditions.

It has been proposed to obviate these difficulties by spraying the solutions under pressure from separate nozzles, the solutions being mixed as they are sprayed. But spray guns and their inherent auxiliaries are quite expensive and bulky, require training of personnel, and are not practical for handling small quantities.

It is the principal object of this invention to provide a silvering apparatus which overcomes the foregoing drawbacks of the premixing and spray systems.

More specifically, it is an object of the present invention to provide a mirror silvering apparatus which mixes solutions just before their application to a mirror, retains the mixture for only a fraction of a second, is so simple in its operation that it can be utilized by untrained help, can silver large or small surfaces with equal ease, constitutes relatively few and simple parts, and, withal, is highly efficient in operation.

It is another object of this invention to provide a mirror silvering apparatus which is comparatively light in weight and does not require bulky, heavy and costly auxiliary equipment.

It is another object of this invention to provide mirror silvering apparatus which is so constructed that regardless of carelessness or lack of skill the various solutions are mixed in correct proportions.

It is another object of this invention to provide a mirror silvering apparatus whose construction is such that it may be quickly and easily disassembled for cleaning and repair.

It is another object of this invention to provide a mirror silvering apparatus which employs parts impervious to the corrosive effects of the silvering solutions wherever the solutions are likely to touch and inexpensive metal parts elsewhere, the apparatus being so constructed and arranged that a minimum of impervious parts are employed.

Other objects of the invention will in part be obvious and in part will be pointed out hereinafter.

The invention, accordingly, consists in the features of construction, combination of elements and arrangements of parts which will be exemplified in the gravity-fed mirror-silvering gun hereinafter described and illustrated,

2

and of which the scope of application will be indicated in the appended claims.

In the drawings in which is shown one of the various possible embodiments of the invention,

Fig. 1 is a top view of a gun constructed in accordance with the present invention;

Fig. 2 is a central longitudinal vertical sectional view through the gun, the same being taken substantially along the line 2—2 of Fig. 1 and showing the gun in inoperative condition;

Fig. 3 is a fragmentary view of one of the valves, the same being taken along substantially the same line as Fig. 2 but illustrating the gun in operative condition;

Figs. 4, 5, 6 and 7 are transverse sectional views of the gun, the same being taken substantially along the lines 4—4, 5—5, 6—6 and 7—7, respectively, of Fig. 2; and

Fig. 8 is an enlarged fragmentary sectional view taken substantially along the line 8—8 of Fig. 6.

Referring now in detail to the drawings, the reference numeral 10 denotes a gravity-fed mirror-silvering gun embodying the present invention. Said gun includes a shell 12 comprising a bottom wall 14, side walls 16, 18 a rear wall 20 and a rearwardly tilted front wall 22. All of the walls are fabricated from a material such, for example, as a synthetic plastic which is chemically inert to the solutions used in silvering of mirrors. Typical plastics which may be employed are cellulose acetate, cellulose acetate butyrate and acrylic resins.

All of the walls are joined to one another in some suitable fashion as, for example, autogeneously or by adhesives. The top of the shell is open. The forward portion of the bottom wall tapers toward the front wall 22, and the side walls 16, 18 converge forwardly, as best shown in Fig. 1, so that the gun can be used in close quarters.

The gun is designed to be employed with plural solutions which are stored in suitable reservoirs, e. g., tanks, at a level above the operating position of the gun so that the solutions can be fed to the gun by gravity. The solutions are introduced to the gun under a relatively low head whereby as later will be appreciated the solutions flow through the gun gently and gently emerge therefrom, not being ejected under great force as is the case with spray guns.

In a typical gun embodying the present invention three fluids are employed, at least one of which contains silver nitrate, one a reducing agent, and one an alkalinizing agent. Hence the gun 10 is illustrated as designed for use with three solutions. It will be understood, however, that this particular number of solutions is not critical and that the gun can be employed with less or more solutions if desired.

The rear wall 20 mounts three hose nipples 24. Said nipples are of conventional construction. Each constitutes a rearwardly extending section 26 formed with a series of external annular grooves 28. The back wall of each groove is perpendicular to the longitudinal axis of the section 26 and the front wall oblique. The tip of the section is conical to facilitate coupling with a hose. Each nipple also includes a central flange 30 and a forwardly extending section 32 having a male thread.

The rear wall 20 is provided with three tapped openings 34. Screwed in each opening is the reduced threaded end 36 of a hose bushing 38 formed of a synthetic plastic. The bore 40 of the bushing is tapped. The enlarged head of the bushing is located within the hollow interior of the shell. The threaded section 32 of each hose nipple is screwed into the threaded bore of a different hose bushing thereby securing the nipple in place.

A packing washer 42 of a compressible synthetic plas-

tic, e. g., an elastomeric resin, is interposed between each flange 30 and bushing 38 thereby effecting a liquid-tight joint at the point where the nipple is connected to the shell.

The nipples are made of metal, being the only components exposed to the silvering solutions which are so fabricated. Hence said nipples are made from a non-corrodible metal, e. g. stainless steel, as contrasted with other metal parts hereinafter described which are made of ordinary steel, iron, brass or the like.

The external surface of the enlarged head of each hose bushing 38 is fashioned with a set of annular grooves 44 to aid in forming a secure joint between said bushing and one end of a short length 46 of flexible tubing fabricated from an elastomeric plastic, such, for example, as a vinyl copolymer. Thus there are three of these lengths of flexible tubing, each one associated with a different one of the hose bushings and nipples. Said lengths of flexible tubing are located within the shell and extend forwardly from the rear wall 20.

The lengths terminate just short of a transverse central wall 48 of a synthetic resin which is fashioned with three tapped openings 50 in alignment with the openings 34. Each opening 50 has screwed therein the forward threaded reduced end of a synthetic resin hose bushing 52. The enlarged head of each bushing 52 protrudes from the rear surface of the wall 48 and is provided externally with annular grooves 54 for facilitating frictional engagement with the forward end of an associated length of flexible tubing 46.

Each of the bushings 52 provides the body of a different valve V. The moving portion of the valve comprises a spindle 56 which is journaled in the cylindrical bore of the bushing 52. Said spindle is formed at its rear end with an enlarged head 58 that is small enough to be freely movable within the associated length of flexible tubing 46 and provide ample space between the head and tubing wall for substantially unrestricted flow of liquid when the valve is open. Said spindle and its head are fashioned from a synthetic plastic.

A washer 60 of an elastomeric plastic encircles the spindle and is located immediately in front of the head 58. Optionally, to insure retention of said washer, the spindle may be formed adjacent said head with a groove 62 in which the washer is seated. It will be appreciated that when the spindle is urged forwardly the washer seats against the rear face of the bushing 52 closing the valve V and permitting no flow of liquid through the gun.

In order to allow liquid to flow through the valve when the washer is shifted off the bushing the spindle 56 is formed with diametrically opposed flats 64 extending through and beyond the bushing. As shown in Fig. 5, this forms a space between opposite sides of the spindle and the bore of the bushing 52. Liquid will flow through these spaces when the washer is lifted off the bushing.

The wall 48 is provided with an upper forwardly extending ledge 66 from whose front edge a support 68 depends. The support includes three openings 70 aligned with the openings 50 and of the proper size to function as journals in which the spindles 56 are translatable. The forward ends of the spindles project from the support and carry abutments 72 near their tips. Helical springs 74 encircling said forward ends are held under compression between the abutments and support and thereby act to bias the spindles forwardly and urge the valves to a closed position.

A synthetic plastic trigger 76 is included for simultaneous manually controlled operation of all the valves. Said trigger is pivoted on a metal cross shaft 78 whose opposite ends are secured in the side wall 16, 18. The trigger comprises a downwardly projecting manually manipulatable finger that passes through a slot 80 in the bottom wall 14 of the shell. The trigger has a short forwardly extending projection 82 at its upper end. This projection bears on the top of one end of a synthetic

plastic rocking arm 84 pivoted on a metal shaft 86 secured in the central wall 48. The other end of the rocking arm is located immediately beneath and in contact with the rearwardly extending arm 88 of a synthetic plastic bell crank lever 90 pivoted on a shaft 92 whose opposite ends are secured in the side walls 16, 18 of the shell. The other arm 94 of the bell crank lever extends downwardly and is located in front of and in contact with the tips of the forward ends of the spindles 56. Thus the springs 74 in addition to biasing the valves V to closed position urge the bell crank lever 90 in a counter-clockwise direction (as seen in Fig. 2) and, therefore, biases the trigger in a like direction. When the trigger is pulled back it will force the spindles rearwardly against the action of the spring to unseat the valve heads 58 and open the valves.

It will be observed that the support 68 terminates well above the bottom wall 14 of the shell. Thus, when the valves are opened silvering solutions will spill out of the hose bushings 52 into the space between the wall 48 and support 68. These solutions will descend under the influence of gravity into contact with the bottom wall 14. In normal use the gun is held in a tilted position, the forward end of the gun being lowermost, so that the silvering solutions will escape from beneath the support 68 and will flow down the bottom wall 14 to the front end of the gun.

To prevent the different silvering solutions from intermixing until the last possible moment a set of vertical partitions 96 is mounted on the bottom wall 14. Said partitions are secured to the front of the central wall 48 and pass through notches 98, 100, respectively, in the support 68 and vertical leg 94 of the bell crank lever. The front ends 102 of the partitions terminate short of the front wall 22 of the shell thereby providing a mixing chamber 104 in which the silvering solutions are combined a moment before they flow out of the gun.

The front wall includes a large threaded aperture 106 in which the rear threaded end of a nozzle 108 is screwed. It will be observed that the longitudinal axis of the nozzle is upwardly inclined with respect to the bottom wall 14 of the shell, this being due to the rearward inclination of the front wall 22. Such tilting of the nozzle is desirable inasmuch as it permits level outflow of the intermixed solutions when the gun is held in a tilted position.

A grip 110 depends from the bottom wall of the casing to facilitate handling of the gun.

It thus will be seen that there is provided a gun which achieves the several objects of the invention and is well adapted to meet the conditions of practical use.

As various possible embodiments might be made of the above invention, and as various changes might be made in the embodiment above set forth, it is to be understood that all matter herein described, or shown in the accompanying drawings, is to be interpreted as illustrative and not in a limiting sense.

Having now described the invention, there is claimed as new and is desired to be secured by Letters Patent:

1. A gravity-fed mirror-silvering hand gun comprising a shell having a bottom wall, side walls, a rear wall, a front wall, and an open top, a plurality of hose nipples mounted in said rear wall and adapted to be coupled to hoses fed by gravity from sources of silvering solutions, a plurality of hose bushings mounted in said rear wall, each bushing being coupled through said wall with a different nipple, a transverse central wall mounted on the bottom wall and spanning the space between the side walls of the shell, a plurality of hose bushings mounted in and extending through said central wall, each of said second named hose bushings being aligned with a different one of the first named hose bushings, lengths of flexible tubing interconnecting the aligned hose bushings, each of the second named bushings constituting a valve body, a spindle axially shiftable in each of said valve bodies and having a head at the rear thereof within the

associated length of flexible tubing, said spindle including a portion projecting forwardly from the central wall, means biasing each of said spindles forwardly so as normally to maintain each head in closed position against the associated valve body, a set of partitions mounted on the bottom wall of the shell and connected with said central wall so as to maintain separately silvering solutions flowing through the different valve bodies, said partitions terminating short of the front wall of the shell to form a mixing chamber for said solutions, a nozzle mounted on said front wall, and manually manipulatable means carried by said shell and effective upon operation thereof simultaneously to shift all of said spindles rearwardly against the force of said biasing means.

2. A gun as set forth in claim 1 wherein the manually manipulatable means comprises a trigger, means rotatably mounting said trigger on the shell, and a kinematic linkage interconnecting said trigger and all of said spindles.

3. A gun as set forth in claim 1 wherein the nozzle is tilted upwardly.

4. A gun as set forth in claim 1 wherein the side walls converge toward the front wall.

5. A gun as set forth in claim 1 wherein a support is carried by the central wall and spaced forwardly thereof, said support being provided with journals in which the spindles are slideable.

6. A gravity-fed mirror-silvering hand gun comprising a shell having a bottom wall, side walls, a rear wall, a front wall, and an open top, means mounted on said rear wall and adapted to be coupled to hoses fed by gravity from sources of silvering solutions, a transverse central wall mounted on the bottom wall and spanning the space between the side walls of the shell, a plurality of hose bushings mounted in and extending through said central wall, each of said hose bushings being aligned with a different one of the coupling means, lengths of flexible tubing interconnecting the aligned hose bushings and coupling means, each of the bushings constituting a valve body, a spindle axially shiftable in each of said valve bodies and having a head at the rear thereof within the associated length of flexible tubing, said spindle including a portion projecting forwardly from the central wall, means biasing each of said spindles forwardly so as normally to maintain each head in closed position against the associated valve body, a set of partitions mounted on the bottom wall of the shell and connected with said central wall so as to maintain separately silvering solutions flowing through the different valve bodies, said partitions terminating short of the front wall of the shell

5 to form a mixing chamber for said solutions, a nozzle mounted on said front wall, and manually manipulatable means carried by said shell and effective upon operation thereof simultaneously to shift all of said spindles rearwardly against the force of said biasing means.

7. A gravity-fed mirror-silvering hand gun comprising a shell having a bottom, sides, a rear, a front and an open top, a plurality of means carried by said shell remote from the front thereof and adapted to be coupled to hoses fed by gravity from sources of silvering solutions, a plurality of valves carried by the shell and each having an inlet and outlet, conduit means connecting the coupling means to the valve inlets, a set of partitions mounted on the bottom of the shell and forming therewith open top channels leading forwardly from the valve outlets so as to maintain separately silvering solutions flowing through the different valves, said partitions terminating short of the front of the shell to form a mixing chamber for said solutions, a nozzle carried on the front of the shell and opening rearwardly to the mixing chamber, and manually manipulatable means carried by said shell and effective upon operation thereof simultaneously to open all of said valves.

8. A gravity-fed mirror-silvering hand gun comprising a shell having a bottom, sides, a rear, a front and an open top, a plurality of means carried by said shell remote from the front thereof and adapted to be coupled to hoses fed by gravity from sources of silvering solutions, a plurality of valves carried by the shell and each having an inlet and outlet, means biasing all of said valves to closed position, conduit means connecting the coupling means to the valve inlets, a set of partitions mounted on the bottom of the shell and forming therewith open top channels leading forwardly from the valve outlets so as to maintain separately silvering solutions flowing through the different valves, said partitions terminating short of the front of the shell to form a mixing chamber for said solutions, a nozzle carried on the front of the shell and opening rearwardly to the mixing chamber, and manually manipulatable means carried by said shell and effective upon operation thereof simultaneously to open all of said valves.

9. A gun as set forth in claim 8 wherein the nozzle is tilted upwardly.
